UNITED STATES PATENT OFFICE.

COSMO LIACI AND ANGELO GIAMMATTEI, OF NEW HAVEN, CONNECTICUT.

MEANS FOR CONVERTING MOTION.

982,077.

Specification of Letters Patent. Patented Jan. 17, 1911.

Application filed February 7, 1910. Serial No. 542,519.

To all whom it may concern:

Be it known that we, COSMO LIACI and ANGELO GIAMMATTEI, citizens of the United States, residing at New Haven, in the county of New Haven and States of Connecticut, have invented a new and useful Means for Converting Motion, of which the following is a specification:

This invention has reference to improvements in means for converting motion and is designed to provide a mechanical movement whereby rotary motion may be converted into continuous rotary motion or intermittent rotary motion differing from the speed and power of the prime mover.

The invention comprises a prime mover having a practically constant speed and means for converting the motion so generated into rotary motion of a different speed or speeds with commensurate available power, and also into intermittent rotary motion in different directions, and likewise provides means for the storage of power until the accumulated power becomes greater than the power of the prime mover and is then utilized either rapidly or slowly in accordance with the work to be performed.

The mechanism is reversible and therefore various types of motion may be converted into continuous rotary motion.

The invention will be best understood from a consideration of the following detail description taken in connection with the accompanying drawings forming a part of this specification, in which drawings—

Figures 1 and 2 taken together constitute a side elevation of the mechanism forming the subject matter of the present invention with some parts shown in section, the two figures over-lapping. Figs. 3 and 4 taken together constitute a plan view of the mechanism shown in Figs. 1 and 2, the two figures over-lapping. Fig. 5 is an end elevation of the structure of Fig. 3. Figs. 6 and 7 are detail views of a clutch mechanism used in the structure. Figs. 8 and 9 are detail views on a larger scale than in Figs. 1 and 3 of an inertia structure used in connection with the invention. Fig. 10 is an elevation of a portion of a lever mechanism used in connection with the structure of Fig. 1.

Referring to the drawings, there is shown a shaft 1 mounted in bearings upon suitable standards 2 which may be supported on a foundation of proper construction, but which

need not be particularly referred to in the description. Carried by the shaft 1 are two inertia members in the form of fly wheels 3, but it will be understood that a single fly wheel may be used or more than two fly wheels if such be found expedient. The rim of each fly wheel is provided with a series of peripheral pockets 4 in each of which is normally housed a block 5 best shown in Fig. 8, this block being sustained by a pivot pin 6 so as to swing into and out of the pocket as may be necessary, to overcome sudden resistance to the rotation of the fly wheel. The block 5 carries a spring 7 which when the block is seated in its pocket 4 is under compression and tends to move the block outward around its pivot pin 6. Each block is formed with a cavity 8 normally entered by one end 9 of a latch lever 10 mounted on the side of the rim of the fly wheel 3 and under the normal control of a spring 11 tending to maintain the end 9 of the latch lever in the cavity 8 and so lock the block 5 against movement about its pivot pin 6 under the action of centrifugal force.

At the end of the lever 10 remote from the end 9 there is a roller 12 designed to engage a fixed stop member 13 by which each lever 11 is carried in the rotation of the respective fly wheel or inertia member 3. The member 13 is carried by a post or standard 14 and is so disposed with reference to the respective fly wheel that when a lever 10 is moved past the stop member 13 the lever is turned on its pivot against the action of the spring 11 to an extent sufficient to withdraw the end 9 of the lever 10 from the cavity 8 and so release the block 5 to outward movement under centrifugal force and the initial impulse given by the spring 7. At another point in the movement of the fly wheel there is a second stop member 15 carrying an anti-friction roller 16 in position to engage the projected block 5 and turn the same on its pivot pin 6 to its seated position in the pocket 4 where it becomes locked by the latch lever 10.

Mounted on the shaft 1 is a pulley 17 connected by a belt 18 to another pulley 19 on a shaft 20 mounted in suitable bearings, and this shaft 20 is shown as immediately beneath the shaft 1 though it may be otherwise located if desirable. The shaft 20 carries a gear wheel 21 in mesh with another gear wheel 22 in turn meshing with a pinion 23 on the same shaft with a gear wheel

24 which in turn meshes with a pinion 25 on a shaft with a gear wheel 26 meshing with another pinion 27 on the same shaft with a gear wheel 28 which in turn is in mesh with a gear wheel 29 on a shaft carrying another gear wheel 30, and the last named gear wheel 30 is in mesh with a gear wheel 31 mounted on a shaft 32 having bearings in standards 33 erected on a suitable support which may be the same upon which the standards 2 are erected. The gear wheel 31 is in mesh with a gear wheel 34 on a shaft 35 mounted in bearings on standard 36, and the gear wheel 34 is in mesh with another gear wheel 37 in turn mounted on a shaft 38 having journal bearings in standards 39. The gear wheel 37 is in mesh with a gear wheel 40 mounted on a shaft 41 having journal bearings in standards 42 and the gear wheel 40 is in mesh with another gear wheel 43 mounted on a shaft 44 having bearings in standards 45. Also the gear wheel 43 is in mesh with another gear wheel 46 mounted on a shaft 47 having bearings in standards 48. The gear wheel 46 is in turn in mesh with a pinion 49 mounted on a shaft 50 having bearings in standards 51 and also carrying fly wheels 52 against the rim of which there may be brought at will the active end of a brake lever 53. The purpose of these several gear wheels will appear hereinafter.

35 Mounted on the shaft 32 on opposite sides of the gear wheel 31 are one-way clutches 54, 55, 56 and 57, best shown in Figs. 6 and 7 where it will be seen that each clutch comprises a casing 58 inclosing a ratchet wheel 59 fast on the shaft 32. In the inner wall of the casing 58 there is formed a cavity 60 housing a pawl 61 urged toward the ratchet wheel by springs 62. When the casing 58 is rotated in one direction the pawl 61 will ride idly over the teeth of the ratchet wheel and when the casing is rotated in the other 45 direction the pawl 61 will engage a tooth of the ratchet wheel and the latter will participate in the rotary movement of the casing 58. The casing of each clutch 55 and 56 carries an arm 63 fast to the casing and 50 having at its outer end a weight 64 which may be as heavy as desired and much larger in proportion than indicated in the drawings where the showing of the weight is simply typical or diagrammatic. The tendency of the weight 64 is to turn the casing 55 or 56 as the case may be in a direction to cause the rotation of the shaft 32. The weighted arm 63 is controlled by a lever 65 through a system of levers similar to a like 55 system shown in Fig. 2 and to be herein-after described, and the lever 65 has its free end in the path of pins 66 on the hub of the gear wheel 34. Each time the gear wheel 34 rotates the two weighted arms 63 are elevated, the corresponding clutches 55 and 56

moving inactively. As soon as the pins 66 pass from engagement with the levers 65 the clutches 55 and 56 are released to the action of the weights 64 and a rotative movement will therefore be imparted to the shaft 32 through a distance agreeable with the movement of the weighted arms. 70

The two clutch members 54 and 57 have their casing provided each with an arm 67 projecting radially therefrom and at the free end pivoted to a post 68 rising from a head 69 lodged in a casing 70 containing a powerful spring 71. The head 67 is provided with anti-friction rollers 72 to ease its movement within the casing. The head 69 of each casing is provided with another standard or post 73 to which is pivoted a lever 74 at an intermediate point in the length of the latter, one end of the lever being pivotally secured to a fixed post or standard 75. The end of each lever 74 remote from its supporting post 75 is pivoted to another lever 76 which in turn is fulcrumed to a fixed post 77 while the other end of each lever 76 is in the path of radial arms 78 rotatable about the axis of the shaft 32, these arms being supported by said shaft but not secured thereto. The arms radiate from a hub 79 carrying at the end remote from the arms a worm wheel 80 engaged by a worm 81 on one end of a shaft 82 having journal bearings in a bracket 83 carried by a respective standard 33. It will be understood that there are two worm wheels 80 and worms 81 with their shafts 82 on opposite sides of the gear wheel 31. Each shaft 82 terminates in a bevel gear wheel 84 in mesh with a mutilated bevel gear wheel 85 on the respective ends of a shaft 86 mounted in suitable bearings on the upper ends of standards 87. The shaft 86 carries a pulley 88 connected by a belt 89 to a pulley 90 on the shaft 1. 95

40 Power may be applied to the shaft 1 by means of a belt 91 traveling about a pulley 92 on the shaft 1 and coming from a pulley 93 on the armature shaft of an electric motor 94, but when the power is applied to the other end of the structure then the motor 94 may be replaced by a dynamo from which 100 electric current may be taken off. 105

45 Upon each shaft 38, 41, 44 and 47, there is a one-way clutch 95 with its casing provided with a radially extending arm 96 terminating in a weight 97 of suitable size 120 though only diagrammatically indicated in the drawings. Each arm 96 is connected by a link 98 to one end of a lever 99 having a suitable fixed support while the other end of this lever is pivotally connected to another 125 lever 100 having a fixed fulcrum support while the free end of the lever 100 is in the path of pins 101 on the hubs of the respective gear wheels 37, 40, 43 and 46. When the gear wheels 37, 40, 43 and 46 are rotated 130

then the pins 101 come into engagement with the respective levers 100 thus rocking the levers 99 on their pivotal supports and elevating the respective weighted arms 96, the 5 clutches then moving idly. As soon as the pins 101 move out of engagement with the levers 100, then the weights 97 become active to cause a rotative movement of the casings of the clutches 95 and this movement is 10 transmitted through the ratchet wheels within the casings to the respective shafts 38, 41, 44 and 47 and rotative movement is imparted to the latter in a step-by-step manner, but because of the intermeshing of the 15 gear wheels 37, 40, 43 and 46 the rotative movement of the shafts 38, 41, 44 and 47 will be in opposite directions one with relation to its neighboring shafts. If the motor 94 be energized rotative movement is imparted 20 to the shaft 1 and to the fly wheels or inertia members 3 and movement will be imparted to the train of gear wheels 31, 34, 37, 40, 43 and 46 through the gear train 21 to 30 inclusive, the speeds of the gear wheels being 25 proportionate to the relative sizes of the several transmission gear wheels. This will cause slow step-by-step rotative movement of the shafts 38, 41, 44 and 47 and these shafts may be connected to the work to be performed. 30 At the same time rotative movement is imparted to the shaft 86 by the belt 89 and intermittent rotative movement is imparted to the shafts 82 by the mutilated gear wheels 85. 35 The showing of the drawings is in part diagrammatic, but it will be understood that the proportion of the mutilated gear wheels and of the gear wheels or pinions 84 as well as the worms 81 and worm gears 80 is such 40 that the active portion of each mutilated gear wheel 85 will cause the movement of an arm 78 to an extent sufficient to compress the spring 71 through the lever systems 76 and 74 and then before the active movement 45 of the mutilated gear wheel 85 ceases the lever 76 has escaped from an actuating arm 78 and then the spring 71 compressed by the active movement of an arm 78 is free to expand and so through the arm 67 and 50 corresponding clutch 54 or 57 impart a rotative movement to the shaft 32. The parts may be so proportioned that a strong impulse is imparted to the shaft 32 to cause its rotation in one direction by the 55 expansion of one or both springs 71, depending upon the set of the mutilated gear wheels 85, and then the shaft 32 may be rotated in the opposite direction by the action of the clutches 55 and 56, and since the 60 turn movement of the shaft need perform little or no work, the said shaft 32 may be connected to work requiring a powerful movement in one direction and a comparatively weak movement in the other direction, and 65 these movements of the shaft 32 will in no

manner interfere with the continued though step-by-step forward movement of the shafts 38, 41, 44 and 47, though the rotative movement of these last named shafts may be in reverse directions, but always in one direction so far as any individual one of said shafts 38, 41, 44 and 47 is concerned. 70

The present invention is useful in machines requiring various and complex movements for shaping or bending or both. 75

What is claimed is:

1. In mechanism of the character described, a prime mover, a train of gears connected therewith, a power storage member, means controlled by the gear train for 80 intermittently applying power to the power storage member, a rotative member, and means for coupling the power storage member to the rotative member when the power storage member is released from the control 85 of the gear train.

2. In mechanism of the character described, a prime mover, a train of gears connected therewith, a gravity power storage member, means controlled by the gears, for 90 intermittently applying power to the power storage member, a rotative member, and a means for coupling the power storage member to the rotative member for actuating the latter when the power storage member is 95 released to the action of gravity.

3. In mechanism of the character described, a prime mover, a train of gears connected therewith another train of gears connected with the first named train of gears 100 with the individual gear wheels of the second named train of gears loosely mounted on their shafts, clutches mounted on the shafts of the second-named train of gears, gravity members connected to the clutches for moving them actively, and a lever system connected to each gravity member and controlled by an adjacent gear wheel of the second-named train of gears. 105

4. In mechanism of the character described, intermeshing gear wheels, shafts for the same upon which the gear wheels are loosely mounted, a clutch upon each shaft, a gravity member for each clutch for moving the same actively to rotate the shaft, a lever system for moving the gravity member against the action of gravity and controlled by a gear wheel other than the one mounted upon the shaft carrying the clutch, and means for rotating the gear wheels. 110 115

5. In mechanism of the character described, a shaft, a gear wheel loosely mounted thereon, another gear wheel in mesh with the first named gear wheel, a clutch on the shaft for rotating the same in one direction, 120 a weighted arm connected to the clutch for moving the same actively, means controlled by the second-named gear wheel for moving the weighted arm to store power therein, another clutch upon the shaft, a spring for 125 130

moving the clutch actively to actuate the shaft in a direction opposed to the movement of the shaft under the action of the first-named clutch, and means for storing power in the spring and subsequently releasing said spring.

6. In mechanism of the character described, a prime mover capable of constant progressive movement, a shaft, oppositely 10 acting clutches on the shaft, a spring and connections therefrom to one of the clutches for rotating the shaft in one direction, connections between the prime mover and the spring for alternately storing power in the 15 spring and releasing the same to actuate the

clutch controlled thereby, a gravity member for actuating the other clutch in a direction to rotate the shaft reversely to that of the first clutch, and the connections between the prime mover and the gravity member for alternately storing power therein and releasing it to active movement. 20

In testimony that we claim the foregoing as our own, we have hereto affixed our signatures in the presence of two witnesses.

COSMO LIACI.
ANGELO GIAMMATTEI.
